UNITED STATES PATENT OFFICE

ROBERT H. MUELLER AND EMMETT M. REEDY, OF DECATUR, ILLINOIS, ASSIGNEES TO
MUELLER CO., OF DECATUR, ILLINOIS, A CORPORATION OF ILLINOIS

METHOD OF FORMING STEM GUIDES

Application filed January 14, 1929. Serial No. 332,529.

This invention relates to new and useful improvements in flush valve mechanisms and has for its primary object the provision of an improved flush valve guide which will insure accurate seating of the flush valve and prevent the same from sticking to its seat while at the same time providing means for limiting the movement of the flush valve actuating mechanism.

Another important object of the invention is to provide an improved overflow coupling having the valve seat portion thereof formed to properly cooperate with the improved valve stem guide so that the latter is at all times retained in exact alignment with the center of the valve seat.

A further important object of the invention is to provide a method of forming the valve stem guide and the means for attaching the guide to the overflow coupling simultaneously to insure alignment of the valve stem guide with the center of the valve seat to which the guide is attached.

Other objects and advantages of the invention will become apparent during the course of the following description.

In the accompanying drawings forming a part of the application, and wherein like numerals are employed to designate like parts throughout the several views,

Figure 1 is a side elevation of the invention applied to a flush tank, parts thereof being broken away to illustrate the association of the mechanism with such tank,

Figure 2 is a side elevation of the overflow coupling with the improved guide attached thereto, parts of the guide and coupling being broken away for the sake of illustrating details of construction, and

Figure 3 is a transverse horizontal section of the same taken on the line 3-3 of Figure 2.

Heretofore, in flush valve actuating mechanisms associated with the valves of overflow couplings, a valve stem guide is usually clamped upon the overflow pipe, and considerable difficulty is always experienced in securing and maintaining the guide directly over the center of the valve seat formed on the overflow coupling which gives rise to

improper seating of the rubber flush valve and causes sticking of the valve to its seat, thereby rendering it difficult to open the valve with the usual actuating mechanism to say nothing of the damage incurred upon the valve, by this improper seating and sticking to its seat.

Referring now more particularly to the drawings, the numeral 4 designates a part of the usual type of flush tank having an opening in its bottom for the passage of a depending externally threaded pipe extension 5 formed integral with the overflow coupling 6. This coupling is provided with an annular shoulder 7 above the pipe extension 5 for engagement with a tapered rubber gasket 8 which is drawn into water-tight engagement with the edges of the opening in the bottom of the tank by means of a jam nut 9 threaded upon the pipe extension 5 for engagement with the bottom wall of the tank. As is well understood, this pipe extension 5 is suitably connected with the fixture to be flushed.

Concentric with the pipe extension 5, the overflow coupling 6 is provided with an upstanding annular externally threaded flange 10, the inner periphery 11 of which is tapered to form a substantially conical valve seat which is, of course, arranged concentric with respect to the pipe extension 5.

The overflow coupling 6 is provided with a hollow lateral extension 12 which communicates with the body of the coupling beneath the valve seat 11 and terminates at its outer end in a tubular boss 13 communicating with the hollow body of the overflow coupling and adapted to receive the lower end of an upstanding overflow tube or pipe 14.

The improved valve stem guide comprises an inverted substantially U-shaped yoke 15, the lower ends of the arms of which are cast integral with an internally screw threaded ring 16 at diametrically opposite points thereon, while the medial portion of the arch of the yoke 15 is formed with an elongated vertical extension 17 forming an abutment and provided with a vertically extending elongated opening 18 therethrough, directly over the center of the ring 16. This ring is adapted to be threaded upon the upstanding

threaded flange 10 of the overflow coupling and is therefore exactly concentric with the valve seat 11. The valve stem guide opening 18 being directly in line and above the center 5 of the ring 16, is obviously arranged directly above the center of the valve seat 11.

The method of forming this valve guide insures that the opening 18 will be arranged in direct alignment with the center of the ring 10 16. This is accomplished by holding the yoke 15 in one pair of machine jaws while the valve stem opening 18 is drilled simultaneously with the formation of the threads upon the ring 16.

15 The usual hollow rubber flush valve 19 is adapted to cooperate with the seat 11 and is provided with a detachable stem 20 which as shown, is of uniform diameter where it had a close sliding fit in the elongated guide opening 18 in the valve guide and terminates in an eye 21 which is disposed a slight distance above the enlargement 17 of the yoke when the valve 18 is seated. An actuating link 22 terminates at its lower end in a laterally 20 disposed eye 23 which is slidably engaged with the valve stem 20 between its eye 21 and the top of the enlargement 17, which latter forms an abutment against which the lateral eye engages when the valve is closed. The 25 upper end of the actuating link 22 is extended through an opening 24 in the free end of a rocking lever 25 and is suitably bent to prevent its accidental detachment from this lever. The opposite end of this rocking lever 30 25 is fastened to the shank of a handle 26 which is suitably mounted for turning movement in a wall of the tank 4 in the well-known manner.

In operation, when the handle 26 is turned 40 to the right of Figure 1, it will cause the free end of the rocking lever 25 to raise, causing corresponding movement of the link 22, lifting its eye 23 in engagement with the eye 21 of the valve stem, and thereby causing the 45 valve 19 to be lifted from its seat to permit the outlet of water from the tank. This valve immediately ascends and is prevented from immediate closing by its buoyancy and does not return to its seat until the level of liquid 50 in the tank lowers sufficiently to permit the valve to be sucked down upon its seat by the out-rushing water. As soon as the actuating handle 26 has been released, the weight of the rocking lever 25 causes the actuating link 22 55 to promptly slide down the valve stem until its eye 23 rests upon the abutment 18, thereby allowing for the unobstructed return of the valve to its seat at the proper time. In view of the fact that the valve stem guide 60 opening 18 is arranged directly above the center of the valve seat, there will be no sticking of the valve when urged to an open position and the valve will always be assured of being directed true to its seat due to the fact 65 65 that the elongated opening or bearing 18

is of sufficient length to engage a sufficient portion of the valve stem, as shown, to prevent lateral movement of the valve with respect to its seat during longitudinal movements of the valve and stem, thereby causing the valve 70 to be accurately aligned with its seat during its movement at all times.

It is to be understood that various changes in the size, shape and arrangement of parts 75 may be resorted to without departing from the spirit of the invention or the scope of the appended claim.

What we claim is:

The method of forming stem guides for overflow couplings consisting in forming a 80 yoke upon a ring, forming an elongated guide boss on the yoke and extending the same medially upward from the top curved surface of the yoke and simultaneously forming an opening in the guide boss and threads 85 upon the inner periphery of the ring, whereby to insure the opening in the guide boss being in alignment with the center of the ring when the parts are set up.

In testimony whereof we have hereunto set 90 our hands.

ROBERT H. MUELLER.
EMMETT M. REEDY.
